UNITED STATES PATENT OFFICE.

LLOYD W. BROWN, OF WHEELING, WEST VIRGINIA.

DIE FOR BRICK MACHINES.

Application filed October 11, 1922. Serial No. 593,830.

To all whom it may concern:

Be it known that I, LLOYD W. BROWN, a citizen of the United States of America, and resident of Wheeling, county of Ohio, and 5 State of West Virginia, have invented certain new and useful Improvements in Dies for Brick Machines, of which the following is a specification.

This invention relates broadly to brick- 10 making apparatus, and more specifically to an extrusion die for such apparatus.

The primary object of the invention is to provide a die for the heads of brick machines which may be adjusted to regulate the 15 extent to which the column of clay is compacted and to compensate for wear.

A further object is to provide a die composed of sections which are readily adjustable to meet the compacting requirements of 20 different clays.

A still further object is to provide a die of the character mentioned having novel and improved means providing for proper lubrication of the advancing clay column.

25 In describing the invention in detail, reference is herein had to the accompanying drawings, in which—

Figure 1 is a front elevation of a die embodying my invention;

30 Figure 2 is a view partly in top plan and partly in horizontal section;

Figure 3 is a view partly in side elevation and partly in vertical section;

35 Figure 4 is a front elevation of the centrally disposed sections of the die arranged in working relation; and—

Figure 5 is a section on line 5—5, Fig. 4.

Referring to said drawings, 1 indicates the 40 head of a press of the general type employed in brick machines in which a compressed column of clay is propelled forward to a traveling conveyor, said head being of hollow rectangular form and having a face plate 2 rigidly mounted upon its outer end. Also 45 attached or otherwise disposed in fixed relation to the inner end of said head is a rectangular ring 3.

Arranged interiorly of the head 1 adjacent to each of the side walls thereof is a plurality of vertically disposed bars, herein disclosed as three in number, designated 4, 5 and 6. Also, arranged adjacent to the top and bottom walls of said head are bars 7, 8 and 9 corresponding in number with the side bars. 55 The various bars referred to constitute members of a sectional die and are capable of ad-

justment to provide for compacting the clay of the column to any required extent and also to compensate for wear.

The side members 4, 5 and 6 are snugly 60 fitted in edge-to-edge relation between the face plate 2 and the ring 3 so as to form close joints with each other and with said plate and said ring. Each of said side members is adjustable toward and away 65 from the adjacent side wall of the head 1, being carried by a plurality of stud bolts 10 which are directed through said side wall. Set screws 11 directed through the side wall against the side member following adjustment of the latter by means of the bolts 10 cooperate with said bolts for bracing the member against outward movement.

The top members of the die have their opposite end portions overlying and resting 75 upon the upper end of the side members 4, 5 and 6, while the bottom members have the lower ends of said side members resting thereon, as is best shown in Fig. 4.

Each of the side members 4, 5 and 6 has 80 an inwardly and forwardly inclined disposition, as shown in Fig. 2, and the relative positions of said members is such that the width of the passage between the opposite sides of the die is gradually reduced from the rear end to the front end of the die, thus providing for the gradual compacting of the clay column by reason of the reduction of its cross sectional area as it advances through the die. Further, the side member 5 has its 85 rear edge seated against the adjacent edge of the member 4 with its inner face disposed slightly outward with respect to the plane of the inner face of said member 4. Likewise, the member 6 is disposed with its inner face 90 slightly outward with respect to the plane of the inner face of the member 5. Thus, as is manifest, when the clay column advances from engagement with one of said side members to the next in series, it will engage the 95 latter at a point remote from the joint between such members, leaving an open space or crotch of triangular form adapted for the reception of the steam introduced for lubricating the sides of the column.

Set screws 12 directed through the top and bottom walls of the head 1 into engagement with the adjacent die members 7, 8 and 9 are designed to hold said members in closely seated relation to the ends of the 100 side members 4, 5 and 6 following adjustment of the latter.

The top and bottom die members 7, 8 and 9 have their inner faces provided with slightly inclined or beveled portions 7^a, 8^a and 9^a extending outward in opposite directions from points midway of their rear edges to their ends. Since these portions are not directly contacted by the advancing clay column, slight triangular spaces are afforded between them and the column 10 allowing access of steam to the top and bottom surfaces of the column for lubricating the latter.

Steam enters the space between the bottom wall of the head and the bottom members of the die through a pipe 13, thence passes around between the side walls of the head and the side members of the die. Small transverse notches 14 provided in the end portions of the edge of said side members permit the passage of the steam to the crotches between said members and the column hereinbefore referred to; and from these crotches the steam passes to the open spaces between the top and bottom die 25 members and the column. Thus, the entire outer surface of the column is lubricated in its passage through the die. Escape of the steam is effected through a suitable located pipe 18.

The head 1 is composed of two aligned sections which are rigidly attached by bolts 15, as shown, and interposed between said sections is a metal diaphragm 16 which extends inwardly and is received between the die sections 5 and 6 and between the die sections 8 and 9 for preventing the escape of steam in a forward direction. To provide for lubrication of the column as it passes by the outer end sections or members of the die, a small irregularly shaped notch or passage 17 permitting steam to by-pass the diaphragm 16 is provided in the side member 5.

It will be manifest that the sectional die structure herein described provides not only for adjustment to meet the compacting requirements of different clays and to compensate for wear, but also for convenient and inexpensive replacement or renewal of die sections which become unduly worn.

What is claimed is—

1. An extrusion die for brick machines, comprising, in combination with a substantially rectangular hollow head, a plurality of complemental die members forming each the top, bottom and sides of the die, the members composing each the top and bottom of the die having their ends overlapping the ends of the members of said sides, and means for adjusting the positions of each of the members of the sides with respect to the adjacent walls of said head.

2. An extrusion die for brick machines, comprising, in combination with a substantially rectangular hollow head, a plurality

of complemental die members forming each the top, bottom and sides of the die, the members composing each the top and bottom of the die having their ends overlapping the ends of the members of said sides, means for adjusting the positions of each of the members of the sides with respect to the adjacent walls of said head, and means for firmly seating the members of said top and bottom with respect to said sides.

3. An extrusion die for brick machines, comprising, in combination with a substantially rectangular hollow head, a plurality of complemental die members forming each the top, bottom and sides of the die, the members composing each the top and bottom of the die, having their ends overlapping the ends of the members of said sides, each of the four groups of sections composing the die having the members thereof positioned in edge to edge group relation, and means for adjusting the positions of each of the members of the sides with respect to the adjacent walls of said head.

4. An extrusion die for brick machines, comprising, in combination with a substantially rectangular hollow head, a plurality of complemental die sections forming each the top, bottom and sides of the die, the top and bottom sections having their ends overlapping the ends of said side sections, each of the four sides of the die having the sections thereof positioned in edge to edge relation and the sections of the sides being inwardly and forwardly inclined and adapted to be located with their inner faces in different planes, and means for adjusting said side sections with respect to the adjacent walls of the head.

5. An extrusion die for brick machines, comprising, in combination with a substantially rectangular hollow head, a plurality of complemental die sections forming each the top, bottom and sides of the die, the top and bottom sections having their ends overlapping the ends of said side sections, each of the four sides of the die having the sections thereof positioned in edge to edge relation and the sections of the sides being inwardly and forwardly inclined and adapted to be located with their inner faces in different planes whereby crotches will be formed between said side sections and the advancing clay column, means for adjusting said side sections with respect to the adjacent walls of said head, and means for introducing steam into said crotches.

6. An extrusion die for brick machines, comprising, in combination with a substantially rectangular hollow head, complemental top, bottom and side portions located inward of the walls of said head and relatively arranged to form a forwardly

- tapered passage through which the clay column is advanced, each of said portions being composed of a plurality of die members arranged in edge to edge relation, the side members having inwardly and forwardly inclined inner faces disposed in different planes thereby to form crotches between said members and the clay column adjacent to the joints formed between said members, 5 means for adjusting said side members relative to the adjacent walls of the head, bracing means for said members, and means for introducing a lubricant into said crotches.
7. An extrusion die for brick machines, comprising, in combination with a substantially rectangular hollow head, complementary top, bottom and side portions located inward of the walls of said head and relatively arranged to form a forwardly tapered 10 passage through which the clay column is advanced, each of said portions being composed of a plurality of die members arranged in edge to edge relation, the side members having inwardly and forwardly inclined inner faces disposed in different planes thereby to form crotches between said members and the clay column adjacent to the joints formed between said members, 15 means for adjusting said side members relative to the adjacent walls of the head, bracing means for said members, the inner faces of the members of the top and bottom portions of the die having beveled portions whereby open spaces are formed between said faces and the column, and means for introducing 20 a lubricant into said crotches and said spaces.
- In testimony whereof, I affix my signature in presence of a subscribing witness.
